[57] CLAIM

The ornamental design for a telephone set with display panel and speakerphone, as shown and described.

DESCRIPTION

FIG. 1 is a front, top and right side perspective view of a telephone set with display panel and speakerphone showing our new design in cradled relationship;

FIG. 2 is a front elevational view thereof;

FIG. 3 is a right side elevational view thereof;

FIGS. 4 and 5 are respectively top and bottom plan views thereof;

FIG. 6 is a left side elevational view thereof;

FIG. 7 is a rear elevational view thereof;

FIG. 8 is a bracketed perspective view of the bottom of the handset spaced apart from the stand and a top view of the stand shown with the handset removed.

FIG. 1

FIG. 2

FIG. 3

*FIG. 4**FIG. 5**FIG. 6**FIG. 7**FIG. 8*
